(57) **CLAIM**

I claim the ornamental design for a housing for a biological sample processing apparatus, as shown and described.

DESCRIPTION

FIG. 1 is a front perspective view of a first embodiment of a housing for a biological sample processing apparatus according to the present invention.

FIG. 2 is a right side elevation view of the housing of FIG. 1, the opposite side view being the mirror image of that shown; FIG. 3 is a front view of the housing of FIG. 1;

FIG. 4 is a front perspective view of a second embodiment of the present invention, the second embodiment being identical to the first embodiment except for the appearance of a logo on the front and on one side; and,

FIG. 5 is a front perspective view of a third embodiment of the present invention, the third embodiment being identical to the first embodiment except for the appearance of a logo on the front and on one side.

The symbol and the word DAKO shown in FIGS. 4, and 5 forming part of the claimed design are registered trade-marks of Dako Denmark A/S, a corporation of Denmark, having post office address Pruduktionsvej 42, DK-2600 Glostrup, Denmark.
